UNITED STATES PATENT OFFICE.

GEORGE W. BURNHART, OF DENVER, COLORADO.

ORE-CONCENTRATING APPARATUS.

1,218,977.

Specification of Letters Patent. Patented Mar. 13, 1917.

Application filed July 13, 1914. Serial No. 851,217.

To all whom it may concern:

Be it known that I, GEORGE W. BURNHART, a citizen of the United States, residing in the city and county of Denver 5 and State of Colorado, have invented certain new and useful Improvements in Ore-Concentrating Apparatus, of which the following is a specification.

This invention relates to ore concentrating 10 apparatus, and particularly to such apparatus as makes use of a table or deck across which is run a stream of water while the table is reciprocated for the purpose of separating the concentrates out of the ore material. The invention is concerned mainly 15 with the table or deck of this type of apparatus, and aims to provide a table of a new and improved form of construction whereby the ore concentrating action will be rendered 20 considerably more effective and the capacity of the table materially increased. The improvements involve also a novel form of construction for the take-off or discharge of the concentrates separated while traveling 25 across the table, by means of which further efficiency and increased capacity are obtained.

Having this general object in view, the invention will now be described with reference to one practical embodiment of the same which has been devised for carrying it into practice, as illustrated in the accompanying drawings, in which—

Figure I is a plan view of the table, partly 35 broken away;

Fig. II is a longitudinal section on the line II—II of Fig. I;

Fig. III is a sectional perspective view 40 of the head or ore-receiving end of the table, the section shown being along the line III—III of Fig. I;

Fig. IV is a fragmentary perspective view illustrating the discharge end of the launder or trough;

Fig. V is a sectional detail on an enlarged 45 scale illustrating the action of the water flow in connection with the riffles of the table; and

Fig. VI is a perspective view of one of 50 the sliding gate members at the discharge end of the launder or trough.

Referring to the drawings, only the table proper of the ore concentrating apparatus is shown, the means for supporting and reciprocating the same not being illustrated, 55 since the same may be of any approved form

and constitutes no part of the present invention. The body of the table or deck comprises a bottom plate portion 2 over which is arranged a series of longitudinally extending timbers 4 in slightly spaced relation, and over these timbers in turn is laid a covering 6 of any suitable material, such as linoleum, forming the floor of the table. The table is constructed so that this floor will 60 slope toward one of its longitudinal lines, preferably its middle line as shown, and at the head or ore receiving end of the table another slope is provided from a transverse line 8 to the head end of the table. Secured 65 to the sides of the table are the angle members 10 forming the side retaining walls for the table, to which members 10 are secured brackets 12 for supporting the ore box or other ore-distributing means (not shown), 70 and also the stop-brackets 14 adapted to cooperate with fixed elements or stops 15 in imparting a shock or impact to the table when reciprocated in the direction of its head or ore-receiving end by means of any 75 suitable reciprocating device, such for instance as the fluid pressure motor, 15^a, reference being here made to applicant's Patent #1,142,551, of June 8, 1915, for a full 80 understanding of said motor.

Along the longitudinal line representing the lowest part of the table it is provided with a longitudinal opening 16, below which is carried a launder or trough 18 for the concentrates 21 separated from the ore material in traveling down the table toward the foot or end of the table where the tailings are discharged. This trough or launder is secured to the table at opposite sides of said opening 16, and the channel 19 forming the 90 bottom of the trough is inclined from the foot or tailings end of the table so that the trough increases in depth toward the head of the table where the concentrates are discharged (see Fig. II). The trough is suitably braced at intervals from the sides of the table by means of a series of stays 20. At its deeper end the trough 18 is provided with a gate member 22, sliding vertically 95 within the retaining lugs 23 carried by the sides of the trough, and adapted to operate as a valve for providing an adjustable discharge opening between its lower end and the bottom of the trough (see Fig. IV), said sliding gate member being clamped, 110 when adjusted, by means of a wing nut 24 and a bolt 26 carried by an upright flange

28 at the top of the discharge end of the trough, said bolt extending through a slot 30 in the gate member 22. Adjacent its lower end the gate member 22 is formed with 5 an opening 32, passage through which is adjustably controlled by a second gate member 34 also sliding vertically within said retaining lugs 23 and provided with a slot 36 to accommodate the bolt 26. The lower edge of 10 the gate member 22 has an out-turned portion 38 to form a chute for the material discharged through the opening 32 into a different vertical plane from that discharged from the other opening at the bottom of 15 the trough. As many discharge openings may be provided as may be desired at different elevations, by means of additional sliding gate members on the order of those above described, for the purpose of separating the concentrates according to the 20 layers or grades into which they settle in the trough.

The surface of the table is equipped with a series of riffles or ribs 40 extending from 25 the sides of the table and diagonally across the same in the direction of the head of the table to the opening 16, the riffle nearest the head end of the table extending between the head end of the table and the adjacent end 30 of the opening 16, as illustrated. It will be observed that the side of each riffle or rib 40 facing in the direction of the foot of the table is undercut for the purpose of overhanging and shielding to a certain degree 35 from the water-flow such mineral as becomes lodged against said undercut sides of the riffles by the reciprocating action of the table. Furthermore, the top surface of each riffle extends throughout in the same 40 approximately horizontal plane, so that the only unbroken path for the water-flow is across the top surface of all the riffles at a slight distance above the courses followed by the concentrates along the bases of the 45 riffles toward the opening 16 into the trough (see particularly Fig. V).

With the foregoing construction, it will be understood that the ore concentrates which settle through the sands and waste 50 material as the table or deck is reciprocated will be compelled to move along in the direction of the riffles 40 toward the opening 16, through which they will drop into the launder or trough 18. The slope of the table 55 in the direction of this opening facilitates this travel of the concentrates, and as the action of the table in reciprocating causes the concentrates to be lodged against the undercut faces of the riffles, the concentrates 60 are thus shielded from the force of the water-flow (as illustrated in Fig. V) and allowed to pass down along said overhanging faces without material danger of being dislodged before reaching the opening into 65 the trough. This works a considerable econ-

omy since more of the concentrates are saved which would otherwise pass over the foot of the table with the tailings; and also gives greater capacity because the concentrates travel faster down an incline than they 70 would along a surface more nearly level. The formation of the riffles with their upper surfaces in practically the same plane also aids in bringing about the above result 75 since the current of the water flow is maintained principally above the spaces between the riffles so as to disturb as little as possible the course of the concentrates toward the trough. In these respects, therefore, this 80 combined feature of undercut or overhanging riffles upon a transversely sloping table surface is conceived to possess very important advantages over the types of reciprocating tables heretofore provided for this purpose. The trough 18 is arranged to take the 85 concentrates passing through the opening 16 at any point along the same, and it is apparent that the depth of the trough is so graduated as not only to suit the requirements as to the amount of the material received at the various points along the opening, but also to provide a path of travel for 90 the concentrates which is inclined in the direction in which they are traveling; consequently, the material will move the more 95 rapidly down such an inclined path and thereby make room for more concentrated material, with the result that the capacity of the apparatus is still further increased. The adjustable sliding gates at the discharge 100 end of the trough provide outlet openings at different elevations through which the material may be discharged and at the same time separated according to the layers or 105 grades formed in the trough, thus always insuring clean concentrates as they will be taken from the lowest point in the trough.

While the foregoing represents what is now conceived to be the preferred mode of carrying the invention into practice, the 110 right is reserved to such changes and modifications as may fairly fall within the scope of the appended claims.

Claims:

1. In an ore concentrating apparatus, a 115 table having its upper surface sloping from the sides toward an intermediate line extending longitudinally of the table, and riffles extending across the upper face of the table from said sides diagonally in the direction of the head or ore-receiving end of the table, the entire upper edge of each of said riffles lying in approximately the same horizontal plane, and means for imparting a shake to the table, adapted to propel the 120 concentrates toward the head of the table.

2. In an ore concentrating apparatus, a 125 table having its upper surface sloping from the sides toward an intermediate line extending longitudinally of the table, and rif- 130

5 sles extending across the upper face of the table from said sides diagonally in the direction of the head or ore-receiving end of the table, said riffles being undercut on their sides facing the foot or tailings end of the table, and means for imparting a shake to the table, adapted to propel the concentrates toward the head of the table.

3. In an ore concentrating apparatus, a 10 table having its upper surface sloping from the sides toward an intermediate line extending longitudinally of the table, and riffles extending across the upper face of the table from said sides diagonally in the direction of the head or ore-receiving end of the table, said riffles being undercut on their sides facing the foot or tailings end of the table and the entire upper edges of said riffles lying in approximately the same horizontal plane, and means for imparting a 15 shake to the table, adapted to propel the concentrates toward the head of the table.

20 4. In an ore concentrating apparatus, the

combination of a table having its upper surface sloping from the sides toward an intermediate line extending longitudinally of the table and provided with a longitudinal opening along said intermediate line and with riffles extending across the upper face of the table from said sides to said opening 25 diagonally in the direction of the head or ore-receiving end of the table, said riffles being undercut on their sides facing the foot or tailings end of the table and the entire upper edges of said riffles lying in approximately the same horizontal plane, and a concentrates trough underlying said opening, and means for imparting a shake to the table, adapted to propel the concentrates toward the head of the table. 30

35 In testimony whereof I affix my signature in the presence of two witnesses.
